Primary Examiner — Jennifer L Rempfer(74) *Attorney, Agent, or Firm* — Law Offices of Steven W. Weinrieb(57) **CLAIM**

The ornamental design for a tent, as shown and described.

DESCRIPTION

FIG. 1 is a front, right side, top perspective view of the tent showing my new design;

FIG. 2 is a rear, left side, top perspective view thereof;

FIG. 3 is a rear, right side, bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof; and,

FIG. 10 is a front, right side, top perspective view thereof showing the tent in a state of use.

The broken lines on the surfaces of the tent show stitching that forms no part of the claimed design. The additional broken lines showing environmental guylines and stakes in FIG. 10 also form no part of the claimed design.

1 Claim, 10 Drawing Sheets(56)
